UNITED STATES PATENT OFFICE.

CHARLES F. QUICK, OF DALLAS, TEXAS.

TENNIS RACKET.

Application filed January 17, 1925. Serial No. 3,184.

To all whom it may concern:

Be it known that I, CHARLES F. QUICK, citizen of the United States of America, residing at Dallas, in the county of Dallas and State of Texas, have invented certain new and useful Improvements in Tennis Rackets, of which the following is a specification.

This invention relates to new and useful improvements in tennis rackets.

10 The object of the invention is to provide a tennis racket in which the strings are constantly held under tension, whereby the racket is always in maximum playing condition irrespective of weather or the number of games which have been played.

A particular object of the invention is to provide a racket having resiliently sustained strings, whereby the ball may be driven with more force and at a greater speed than is ordinarily attained with the laced string racket now in common use.

20 A further object of the invention is to provide means for varying the tension exerted on the strings, together with a novel form of string spacing and supporting devices.

25 A construction designed to carry out the invention will be hereinafter described together with other features of the invention.

30 The invention will be more readily understood from a reading of the following specification and by reference to the accompanying drawings, in which an example of the invention is shown, and wherein:

35 Fig. 1 is a plan view of a racket constructed in accordance with my invention.

40 Fig. 2 is a side elevation of the same, a portion of the handle being illustrated in section, and

45 Fig. 3 is an enlarged detail of the string mountings.

In the drawings the numeral 10 designates an elliptical frame having the general shape of the ordinary tennis racket now in common use. At the base of the frame is a cross bar 11 and a yoke 12. A suitable handle 13 is secured in the yoke. This handle may be counter-bored at 14 either to lighten the weight or to receive a weight. By this means the racket is balanced.

50 The frame 10 may be made of any suitable material, such as metal, bamboo, wood or other material suitably formed or built

up. The frame has a channel 15 open 55 around its outer side. In the bottom of the channel are spaced bosses 16 having flat heads. Strings 17 and 18 are laced, respectively longitudinally and transversely of the frame, alternately crossing each other in the 60 manner common to the lacing of tennis rackets. These strings may be of wire, gut or any other material suitable for the purpose.

65 One of the features of the invention are curved stirrups 19 around which the strings are looped. These stirrups space the complementary lengths or strands apart and thus give to the lacing the proper mesh. As the strings are looped around the stirrups, 70 sharp or acute bends are thus avoided. For securing the ends of the strings posts 20 are fastened in the channel of the frame. Each end of the string is fastened to a post, as is shown best in Fig. 3, and the string is passed 75 through an aperture 21' in the frame.

Each stirrup is supported in the eye 21 on the inner end of a stem 22. Each stem passes through an aperture 23 in the frame and the boss 16, except at the bar 11 where the bosses 80 are omitted, and has its outer end screw threaded. A spanner nut 24 is mounted on each stem and has a reduced shank 25 for engaging in the outer end of a coiled spring 26 surrounding the stem and resting against 85 the boss.

The strings are looped around the stirrups 19 which have their convex sides grooved to receive the strings. The stirrups thus support the ends of the loops. The nuts are 90 adjusted to draw the string taut and to place the springs under compression. It will be seen that the nuts may be adjusted to tension the springs to the desired degree as well as to stretch the strings as desired.

95 Owing to the curvature of the stirrups the strings will readily slide through the grooves thereof when the nuts are tightened. The strings are unlikely to be broken because the springs yield when the ball is struck. By reason of the rebound incidental to the yielding of the springs and strings, the ball is gotten away with greater force and speed. Should the strings require adjusting at any time it is merely necessary to turn the nuts 24 and increase the tension of the springs. However the tension of the springs is sufficient to compensate consider-

able variation in the tautness of the strings.

Various changes in the size and shape of the different parts, as well as modifications and alterations may be made within the 5 scope of the appended claims.

What I claim is:

1. In a tennis racket, a frame, a plurality of resiliently sustained members movable through the frame, and strings carried by 10 said members.
2. A tennis racket comprising resiliently supported strings, and means for varying the tension on the strings.
3. In a tennis racket, a frame, a plurality of spring tensioned members, strings supported by said members, and means for 15 varying the tension of said members.
4. In a tennis racket, a frame, a plurality of strings meshed within the frame, and 20 means for resiliently supporting the strings adjustable to give a substantially uniform tension to the strings.
5. In a tennis racket, a frame, strings laced across the frame, and adjustable spring 25 tensioned supports for the strings carried by the frame.
6. In a tennis racket, a frame, strings looped across the frame, and adjustable

spring tensioned supports for the ends of the loops carried by the frame.

7. In a tennis racket, a frame, resiliently supported stirrups carried by the frame, and strings looped from one stirrup to another.

8. In a tennis racket, a frame, strings looped across the frame, curved stirrups supporting the ends of the loops and spacing the strands of the loops apart, and spring tensioned supports for the stirrups engaged in the frame.

9. In a tennis racket, a frame, stems slid- 40 able in the frame, stirrups carried by the stems; strings looped from one stirrup to another, coiled springs on the stems, and adjusting nuts on the stems bearing against 45 springs.

10. In a tennis racket, a frame having a channel therearound, stems slidable through the frame and having eyes, curved stirrups in the eyes within the frame, strings looped across the frame and seated in the stirrups, 50 coiled springs surrounding the stems within the channel of the frame, and tension nuts mounted on the stems and engaging the springs.

In testimony whereof I affix my signature.

CHARLES F. QUICK.
